UNITED STATES PATENT OFFICE

ARTHUR L. SHAW, DECEASED, LATE OF CICERO, ILLINOIS, BY BERTHA S. SHAW, EXECUTRIX, OF CICERO, ILLINOIS, ASSIGNOR TO CHICAGO AUTOMATIC CONVEYOR CO., OF CICERO, ILLINOIS, A CORPORATION OF ILLINOIS

PORTABLE CONVEYER

Application filed January 20, 1930. Serial No. 421,910.

The present invention relates generally to portable conveyers which are adapted for use in moving coal, coke, crushed stone, gravel or other such material from a pile on the ground to a wagon, pit car, or another conveyer. More particularly the invention relates to that type of portable conveyer which consists of an elongated conveyer-frame, the receiving end of which is adapted to rest upon the ground, an endless conveyer element operating in and supported by the frame, a motor having power-transmitting mechanism associated therewith for driving the conveyer element, and a wheel-equipped frame which serves to support the conveyer-frame so that the discharge end thereof may be raised or lowered in order that the same may be adjusted to the proper height for discharge onto the wagon, pit car or second conveyer with which the conveyer-frame is associated.

One object of the invention is to provide a portable conveyer of the type under consideration embodying means of an improved character for adjustably supporting the conveyer-frame with respect to the wheel-equipped frame.

Another object of the invention is to provide a portable conveyer of the aforementioned type in which the frame that serves to support adjustably the conveyer-frame is equipped with a pair of flanged wheels at the sides thereof for travel on a pair of rails, and embodies means which operates, during raising of the conveyer-frame, to cause the flanged wheels to be elevated out of engagement with the rails into a position wherein the conveyer may be readily derailed.

Another object of the invention is to provide a portable conveyer in which the sides of the conveyer-frame are formed of wrought metal plates which are arranged to form a compartment for housing the motor for the conveyer element and the power-transmitting mechanism which is driven thereby.

A further object of the invention is to provide a novel lubricating system and an improved power-transmitting or driving mechanism for a conveyer-element of the chain and drag bar type.

A still further object of the invention is to provide a portable conveyer which is efficient in operation, may be manufactured at a comparatively low cost and is generally of an improved character.

Other objects of the invention and the various advantages and characteristics of the present construction will be apparent to those skilled in the art from a consideration of the following detailed description.

The invention consists in the several novel features hereinafter set forth and more particularly defined by the claims at the conclusion hereof.

In the drawings which accompany and form a part of this specification or disclosure and in which like numerals of reference denote corresponding parts throughout the several views:

Figure 1 is a vertical longitudinal section of a conveyer embodying the invention;

Figure 2 is a plan view, parts being shown in section for purposes of illustration;

Figure 3 is a perspective view;

Figure 4 is a side elevational view illustrating in detail the manner in which the derailing means operates to cause the flanged wheels to be elevated out of engagement with the subadjacent portions of the rails when the conveyer-frame is raised;

Figure 5 is an enlarged transverse section taken on the line 5—5 of Figure 1;

Figure 6 is a detail of one of the oiling devices of the lubricating system for the conveyer element; and

Figure 7 is a detail view of a part of the gearing which forms the power-transmitting mechanism between the motor and the endless conveyer element.

The conveyer which forms the subject matter of the invention is adapted for use in moving coal, coke, crushed stone, gravel or other such material from a pile on the ground to a wagon, pit car or second conveyer, and comprises an elongated conveyer-frame 10. The latter is associated with a wheel-equipped frame 11 so that it may be properly positioned with respect to the material to be conveyed and may be moved from one place to another. The conveyer-frame 10 consists

of a pair of sides, each of which is made up of a series of wrought metal plates 12, 13, 14 and 15. The plates of each side are welded or riveted together so as to form a rigid structure. The plates 12, 13 and 14 of the conveyer-frame form the receiving end of the conveyer and are so arranged that such end is of an inclined character. The plates 15 form the discharge end of the conveyer, 5 extend horizontally and are reinforced at their inner ends by plates 16 which are riveted or otherwise secured to the plates 14. The two sides of the conveyer-frame are cross connected by a substantially imperforate apron 17. The latter extends from one end of the conveyer-frame to the other and underlies the upper reach of an endless conveyer element 18. The side margins of the apron are associated with a pair of angle iron bars 19. These 10 bars comprise horizontally extending legs 19^a and vertically extending legs 19^b. The legs 19^a fit against and are welded to the bottom face of the apron 17. The vertically extending legs 19^b depend from the legs 19^a and 15 are riveted to the wrought metal plates which form the sides of the conveyer-frame. The receiving end of the apron 17 is inclined and extends upwardly from the plates 12. The discharge portion of the apron extends horizontally and is positioned midway between the top and bottom edges of the plates 15. The lower portions of the plates 13 form with the apron 17 a compartment 20. The lower part of this compartment is closed by a bottom plate 21 which is secured in any suitable manner to the bottom margins of the plates 13. The front end of the bottom plate is extended so as to underlie the receiving end of the apron 17 and is secured to the bottom margins of the plates 12. The rear end of the bottom plate 21 is disposed beneath the plates 14, extends horizontally and is associated with a pair of angle iron bars 22. The latter comprise horizontally extending legs 22^a and 20 vertically extending legs 22^b. The horizontally extending legs 22^a fit against the top face of the plate 21 and are riveted or otherwise secured in place. The vertically extending legs 22^b of the bars 22 extend upwardly from the legs 22^a and are secured at their front ends to the plates 13. The rear ends of the bars 22 are supported in spaced relation with respect to the plates 14 by an outer vertically extending pair of angle iron uprights 23 and an inner vertically extending pair of uprights 24. The uprights 23 comprise longitudinally extending legs 23^a and laterally extending legs 23^b. The upper ends of the legs 23^a are riveted to the reinforcing plate 16. 25 The lower ends of the longitudinally extending legs 23^a are riveted to the rear ends of the legs 22^b of the bars 22. The laterally extending legs 23^b of the uprights 23 extend outwardly with respect to the legs 23^a. The uprights 24 comprise longitudinally extending

legs 24^a and laterally extending legs 24^b. The legs 24^a are positioned in parallel relation with the legs 23^a of the uprights 23 and serve to form with said last mentioned legs vertically extending guideways 25. The upper ends of the longitudinally extending legs 24^a of the uprights 24 are riveted to the reinforcing plates 16. The lower ends of said legs 24^a are riveted to the legs 22^b of the bars 22^b. The legs 24^b project outwardly from the legs 24^a. 30

The endless conveyer element 18 comprises a pair of chains 26 which are associated with the sides of the conveyer-frame and are cross connected by drag bars 27. The latter are provided at the ends thereof with brackets 28 which are secured to oppositely facing pairs of chain links. The receiving ends of the conveyer chains 26 extend around and are supported by a pair of sprocket wheels 29 which are mounted on a shaft 30. The latter is mounted in a cast metal boot plate 31 which is secured to the front ends of the plates 12 and is adapted to rest upon the ground. The discharge ends of the conveyer chains extend around and are supported by a pair of wheels 32 which are mounted on a shaft 33. The latter is journaled in a pair of bearings 34 which are secured to the extreme rear ends of the horizontally extending plates 15. The drag bars 27, during travel in the upper reaches of the conveyer chains, rest upon the apron 17 and serve to drag the material that is to be conveyed from one end of the conveyer to the other. The upper reaches of the conveyer chains are covered by a pair of angle iron bars 35. The latter are secured to the upper marginal parts of the plates 12, 13, 14 and 15 and are provided with inwardly extending legs 35^a which extend over and cover the upper reaches of the chains 26. The lower reaches of the conveyer chains are supported at the rear ends thereof by a pair of angle iron bars 36. The latter are secured to the lower marginal parts of the horizontally extending plates 15 and are provided with inwardly extending horizontal legs 36^a. The front ends of the lower reaches of the conveyer chains are supported by a pair of idler wheels 37, a pair of idler wheels 38 and a pair of idler wheels 39. The idler wheels 37 are mounted on a cross shaft 40 which is journaled in bearings 41 on the plates 16. The idler wheels 38 are mounted on a cross shaft 42 which extends across the entrance to the compartment 20 and is journaled in bearings 43 on the plates 13. The idler wheels 39 are mounted on a cross shaft 44 which is located adjacent the central portion of the plates 13 and is journaled in a pair of bearing blocks 45. The latter are slidably mounted and are adapted to be shifted by a pair of bolts 46 in order to take up the slack in the chains 26. The conveyer element 18 is driven by an electric motor 47 which is mounted on the rear end of the bottom plate 21 and is dis-

posed beneath the plates 14 of the conveyer-frame. The driving connection between the motor and the conveyer element comprises a sprocket 48 which is fixed to one end of the 5 rotor shaft of the motor; a sprocket wheel 49 which is fixed to a cross shaft 50 and is driven from the sprocket 49 by an endless chain 51; a sprocket 52 which is fixed to the cross shaft 50; a sprocket wheel 53 which is mounted on a cross shaft 54 and is driven from the sprocket 52 by an endless chain 55; and a pair of sprockets 56 which are fixed to the cross shaft 54 and serve to drive the conveyer chains 26. The cross shaft 50 is journaled in a pair of bearings 57 which are secured to the rear ends of the plates 13. The cross shaft 54 is mounted in a pair of bearings 58 and is positioned so that the sprockets 56 engage the conveyer chain between the 10 idler wheels 38 and 39. The bearings 58 are secured to the plates 13 of the conveyer-frame. The sprocket wheel 53 is drivably connected to the cross shaft 54 by means of a collar 54^a. The latter is keyed to the cross shaft and rigidly connected to the sprocket wheel 53 by means of a bolt 55^a. This bolt operates as a safety device in that it shears off whenever the conveyer-element 18 becomes locked for any reason and thus prevents 15 breakage of the chains 26. The sprocket wheel 49 and the chain 51 are disposed in the compartment 20.

Oil or a similar lubricant is applied to the conveyer chains 26 by a pair of horizontally extending lubricating devices 59 and 60. These devices are preferably formed of a piece of pipe and are disposed above the lower reaches of the conveyer chains. The device 59 is located between the sprocket 25 wheels 29 and the idler wheels 39 and extends through aligned apertures 61 in the plates 13 of the conveyer frame. One end of the device 59 is closed by a cap 62 which fits against the outer face of one of the plates 13. The other end of the device 59 is provided with an upwardly extending filling or elbow 63 which forms an inlet 63 for receiving oil. A pair of openings 59^a are formed in the bottom portion of the device 59 and permit the oil to flow drop by drop onto the conveyer chains. The inlet 63 is normally closed by a removable cap 64. The lubricating device 60 is similar in construction to the device 59, embodies a pair of discharge openings 60^a and is located between the idler wheels 38 and the sprockets 56. By locating the device 60 in the manner set forth, the links of the conveyer chains are provided with oil prior to contact thereof with the sprockets 56.

The frame 11 comprises a pair of flanged wheels 65 which are adapted to travel either on the ground or on a pair of rails 66. The hubs 65^a of the wheels are rotatably mounted on the ends of an axle 67 which is positioned

beneath the rear end of the bottom plate 21 and serves to support the wheels so that they are located outwardly of the sides of the conveyer-frame. The axle 67 is secured by U-bolts 68 to the central parts of a pair of channel iron beams 69. The latter comprise laterally extending flanges 69^a and 69^b and are arranged so that such flanges extend outwardly. The U-bolts 68 extend through the flanges 69^b and are held in place by nuts 70. The beams 69 are pivoted at the front ends thereof to the rear lower portions of the plates 13 so that they are free to swing vertically. The rear ends of the beams are cross connected by a channel iron bar 71 which is arranged so that the flanges thereof project toward the front end of the conveyer and lap the front ends of the flanges 69^a and 69^b of the beams 69.

A pair of vertically extending channel iron beams 72 are disposed at the rear ends of the beams 69. These beams are arranged so that the flanges thereof project outwardly. The lower ends of the beams 72 are pivotally connected by bolts 73 to a pair of brackets 74 which are rigidly secured to the rear ends of the flanges 69^a of the beams 69. The upper ends of the vertically extending beams 72 are provided with a pair of angle iron brackets 75. These brackets comprise horizontally extending legs 75^a and vertically extending legs 75^b and are arranged so that the horizontally extending legs rest on the upper ends of the beams 72. The brackets 75 are held in connected relation with respect to the channel iron beams 72 by means of brackets 76. The latter are attached to the upper ends of the beams 72 and are provided with outwardly extending legs 76^a which lap and are rigidly secured to the horizontally extending legs 75^a of the brackets 75. A pair of bearing members 77 are secured by bolts 78 to the legs 76^a of the brackets 76. These bearings support rotatably a shaft 79 which extends through and is vertically movable in the guideways 25, and is provided with a pair of pinions 80. These pinions are fixedly secured to the shaft 79 and mesh with a pair of racks 81. The latter are associated with the uprights 23 and are mounted on vertically extending angle iron bars 82 which are rigidly secured to the longitudinally extending legs 23^a. When the shaft 79 is rotated in one direction, the pinions 80 operate to shift upwardly the racks 81 and thereby effect raising of the discharge end of the conveyer. Reverse rotation of the shaft 79 causes the pinions 80 to lower the racks 81 and the horizontally extending discharge part of the conveyer-frame. The shaft 79 is rotated to effect the desired raising or lowering of the conveyer-frame by means of a lever 83 which is loosely mounted on one end of said shaft 79 and is provided with a pawl 84. The latter operates in conjunction

with a ratchet wheel 85 which is fixedly secured to the shaft 79. When the lever 83 is shifted in one direction, the shaft 79 is caused through the medium of the pawl and ratchet wheel, to rotate the pinions so as to elevate the conveyer-frame 10. Reverse rotation of the shaft 79 is normally prevented by a dog 86 which is pivotally connected to a pin 87 on the leg 75^b of the bracket 75 and cooperates with a ratchet wheel 88. The ratchet wheel 88 is fixedly secured to the shaft 79 inwardly of the ratchet wheel 84. When it is desired to lower the conveyer-frame, the dog 86 is swung out of engagement with the ratchet wheel 88. In this position of the dog, the shaft 79 is free so that it may be rotated in a reverse direction in order to permit of the lowering of the conveyer-frame. The rack and pinion connections (80, 81) together with the vertically extending channel iron beams 72, exemplify means of an improved character for supporting the conveyer-frame 10 adjustably with respect to the wheel-equipped frame 11.

25 In some instances it is desirable to derail the conveyer so that it may be wheeled on the ground from one place to another. To permit of ready derailment a leg 89 is provided. This leg is preferably formed of channel iron and has one end thereof pivotally connected to the central portion of the bar 71 by means of a bolt 90. The leg is of such length that when it is swung downwardly into a vertical position, the lower end thereof is adapted to rest directly upon the subjacent ground. When the leg 89 is in its operative position raising of the conveyer-frame by manipulation of the lever 83 causes the conveyer to be elevated into a position wherein it may be readily derailed. This is caused for the reason that the leg serves as a support or fulcrum for the rear end of the wheel-equipped frame 11 and raising of the conveyer frame tends to elevate the front ends of the channel iron beams 69. Since the wheels are carried by the central parts of the beams 69 it is manifest that upward swinging movement of said beams with the leg as a fulcrum causes the wheels to be elevated with respect to the rails into the position indicated by dotted lines in Figure 4. When the conveyer is supported by the leg 89 and the wheels 65 are elevated with respect to the rails, derailment may be effected simply by pushing the conveyer sidewise in one or the opposite direction. The leg is carried, when in its inoperative position, by a hook or stirrup 91 which is secured by a bolt 92 to one end of the bar 71 and is adapted to receive the distal end of the leg and to support the leg in a horizontal position.

50 The operation of the conveyer will be as follows:

Assuming that the wheels 65 of the frame 11 are supported on the rails 66, the conveyer

is wheeled into a position wherein the receiving end thereof rests upon or is positioned adjacent to the material that is to be elevated or conveyed. The conveying operation is started by applying electrical energy or current to the motor 47. Drive of the motor serves to actuate the conveyer element through the medium of the various chain and sprocket connections. During actuation of the conveyer element 18 the material is shovelled onto the receiving end of the conveyer where it is engaged by the drag bars 27 and propelled over the apron 17 to the discharge end of the conveyer. During operation of the conveyer chains the lubricating devices 59 and 60 cause drops of oil to be fed to the chains for lubrication purposes. If the conveyer element becomes locked by reason of material jamming into engagement with the chains 26 or for any other reason the sprocket wheel 53 operates to shear the bolt 55^a. As soon as the bolt becomes sheared, the motor 47 imparts no further drive movement to the shaft 54 and hence cannot cause breakage of the chains 26.

55 In the event that it should be desired to derail the conveyer so that it may be transported or moved on the ground from one place to another, the leg 89 is swung out of supported relation with respect to the stirrup 91 and positioned in a vertical position as indicated in Figure 4. The lever 83 is then reciprocated back and forth to cause through the medium of the pawl and ratchet and pinion and rack connections elevation of the conveyer-frame. As previously pointed out, raising of the conveyer-frame tends to raise the front ends of the channel iron beams 69. Since the fulcrum for the wheel-equipped frame 11 is changed to the leg 89, raising of the beams 69 causes the wheels 65 to be raised or elevated out of engagement with the subjacent portions of the rails 66. When the conveyer is supported by the leg 89 with the wheels in elevated relation, the conveyer is pushed sidewise. During the pushing operation, the leg 89 swings sidewise and causes the conveyer to be shifted so that the wheels are deposited on the ground. After the derailment operation, the conveyer element may be lowered by swinging the dog 86 out of engagement with the ratchet wheel 88. Disengagement of the dog releases the shaft 79 so that it permits the conveyer-frame to lower by gravity. The lowering operation may be controlled by holding or retarding movement of the lever 83. When the conveyer-frame is lowered to the desired position, the dog 86 is swung back into engagement with the ratchet wheel 88 so as to lock the shaft 79 against rotation. Raising of the conveyer-frame is accomplished by reciprocating the lever 83, as previously pointed out, so as to cause rotation of the shaft 79 through the pawl and ratchet connection 84 and 85. Ro-

tation of the shaft 79 causes the pinions 80 to raise or force upwardly the racks 81. The shaft 79 which is located at the upper ends of the channel iron beams 72 is confined between the uprights 23 and 24 and therefore cannot be displaced in a forward or rearward direction.

The conveyer disclosed herein is exceedingly efficient in operation by virtue of the fact that the chains of the conveyer element 18 are lubricated and the various driving instrumentalities are housed in the compartment 20. Since but a few parts are used the conveyer may be manufactured at a comparatively low cost.

The invention is not to be understood as restricted to the details set forth, since these may be modified within the scope of the appended claims, without departing from the spirit and scope of the invention.

Having thus described the invention, what is claimed as new and desired to be secured by Letters Patent, is:

1. In a portable conveyer, the combination of an elongated frame having one end thereof adapted to rest upon the ground, an endless conveyer means carried by and operable in said frame, a structure for sustaining the other end of the frame pivotally connected at one end thereof to the frame and embodying a pair of wheels, an upstanding beam having the lower end thereof connected pivotally to the other end of the structure, and means for raising and lowering the said other end of the frame comprising a pinion rotatably mounted at the upper end of the beam and a rack connected fixedly to the frame.

2. In a portable conveyer, the combination of an elongated frame having one end thereof adapted to rest upon the ground and provided at the central portion thereof with means forming a substantially vertical guideway, an endless conveyer means carried by and operable in said frame, a structure for sustaining the other end of the frame pivotally connected at one end thereof to the frame and embodying a pair of wheels, an upstanding beam having the lower end thereof connected to the other end of the structure and provided with a member at its upper end extending through and slidable in the guideway, and means for raising and lowering the said other end of the frame comprising a rack and pinion connected between the frame and the beam.

3. In a portable conveyer, the combination of an elongated frame having one end thereof adapted to rest upon the ground and provided at the central portion thereof with means forming a substantially vertical guideway, an endless conveyer means carried by and operable in said frame, a structure for sustaining the other end of the frame pivotally connected at one end thereof to the frame

and embodying a pair of wheels, an upstanding beam having the lower end thereof pivotally connected to the other end of the structure and provided at its upper end with a horizontally extending shaft projecting through and slidable in the guideway, and means for raising and lowering the said other end of the frame comprising a pinion on the shaft and a rack secured to the frame adjacent the guideway.

4. In a portable conveyer, the combination of an elongated frame having one end thereof adapted to rest upon the ground and provided at the central portion with a pair of uprights spaced apart to form a vertical guideway, an endless conveyer means carried by and operable in said frame, a structure for sustaining the other end of the frame pivotally connected at one end thereof to the frame and embodying a pair of wheels, an upstanding beam having the lower end thereof pivotally connected to the other end of the structure and provided at its upper end with a horizontal shaft extending through and slidable in the guideway, and means for raising and lowering the said other end of the frame comprising a pinion on the shaft and a rack secured to one of the uprights.

5. In a portable conveyer, the combination of an elongated frame having one end thereof adapted to rest upon the ground, an endless conveyer means carried by and operable in said frame, a structure for sustaining the other end of the frame embodying a pair of wheels adapted to travel on rails, means for raising and lowering the said other end of the frame relatively to the wheel-equipped structure, and means operative in response to manipulation of the raising and lowering means to cause the structure to be shifted into a position wherein the wheels are raised off the rails upon which they are adapted to travel.

6. In a portable conveyer, the combination of an elongated frame having one end thereof adapted to rest upon the ground, an endless conveyer means carried by and operable in said frame, a structure for sustaining the other end of the frame embodying a pair of wheels adapted to travel on rails, means for raising and lowering the said other end of the frame with respect to the wheel-equipped structure, and means operative in response to raising of the frame to cause the structure to be shifted into a position wherein the wheels are raised off the rails upon which they are adapted to travel.

7. In a portable conveyer, the combination of an elongated frame having one end thereof adapted to rest upon the ground, an endless conveyer means carried by and operable in said frame, a structure for sustaining the other end of the frame pivotally connected at one end thereof to the frame and embodying

at its central portion a pair of wheels adapted to travel on rails, means for raising and lowering the said other end of the frame relatively to said structure, and a leg mounted on the other end of the structure and operative in response to raising of the frame to cause the structure to be lifted into a position wherein the wheels are raised off the rails on which they are adapted to travel.

13 8. In a portable conveyer, the combination of an elongated frame having one end thereof adapted to rest upon the ground, an endless conveyer means carried by and operable in said frame, a structure for sustaining the other end of the frame pivotally connected at one end thereof to the frame and embodying at its central portion a pair of wheels adapted to travel on rails, means for raising and lowering the said other end of the frame relatively to said structure, and a leg pivotally connected to the other end of the structure and adapted to be swung downwardly into a position wherein it is operative in response to raising of the frame to cause the wheels to be raised off the rails.

18 9. In mechanism for conveying material, the combination of an elongated supporting frame comprising sides, an endless conveyer supported between the sides of the frame and consisting of a pair of chains and drag bars between the chains and mechanism for driving the conveyer embodying a motor, a shaft journalled in the sides of the frame and provided with a drive member rigidly secured thereto, a wheel driven by the motor and loosely mounted on the shaft adjacent said driving member, a pair of sprockets engaging the chains and connected to be driven by the shaft, and a driving connection between the gear and the aforesaid member comprising a bolt extending through said wheel and member, said bolt being adapted, when the conveyer is locked or jammed, to be sheared so as to render inoperative the conveyer driving mechanism and thereby prevent breakage of the chains.
